UNITED STATES PATENT OFFICE

JOHN C. KORTICK, OF SAN FRANCISCO, CALIFORNIA

FIRE-FIGHTING TOOL

Application filed September 26, 1927. Serial No. 222,064.

My invention relates to improvements in fire fighting tools, and it consists in the combinations, constructions, and arrangements hereinafter described and claimed.

5 An object of my invention is to provide a fire fighting tool in which novel locking means is provided for rigidly securing the blade to the handle, this means preventing the accidental flying off of the blade from 10 the handle, and also preventing rotation of the blade with respect to the handle.

A further object of my invention is to provide a device of the type described which is 15 extremely simple in construction, and which is durable and efficient for the purpose intended.

Other objects and advantages will appear in the following specification, and the novel features of my invention will be particularly 20 pointed out in the appended claims.

My invention is illustrated in the accompanying drawing forming a part of this application, in which:

Figure 1 is a perspective view of the device;

Figure 2 is a section along the line 2—2 of Figure 1;

Figure 3 is a section along the line 3—3 of Figure 1; and

30 Figure 4 is a perspective view of a part of the device.

In carrying out my invention I provide a handle 1, which is constructed of a wooden piece 2, and a metallic piece 3. The piece 3 35 has a ferrule 4 that is disposed quite a distance from the head 5 of the piece. This construction is for the purpose of removing the wooden part of the handle quite a distance away from the blade 6, so that the wood will 40 not likely be charred by the flames. I have found that when the ferrule is disposed adjacent to the blade and the wooden handle mounted in the ferrule, the flame will heat the ferrule and will char the wood to such an extent as to loosen the wood within the ferrule. By disposing the ferrule a suitable distance 45 away from the blade I overcome this disadvantage. A rivet 7 secures the wooden handle 2 to the ferrule 4.

50 Figures 2 and 3 show novel means for per-

mitting the blade 6 to be removably secured to the part 3 and when so secured to be prevented from accidental withdrawal from the part. Many tools having detachable blades are unsafe, because the blades oftentimes fly 55 off while the tool is being used. To overcome this objection I have provided a head 5 of the shape shown in Figure 1 and have mounted this head upon the threaded portion 8 of the part 3. The end of the part 3 is upset as at 9 60 and this construction rigidly secures the head to the part 3 and also prevents rotation between the two elements.

The blade 6 has a wedge-shaped opening 10 therein, see Figure 1, through which the head 5 may be threaded when the blade is turned at right-angles to that shown in Figure 2. The blade when being mounted upon the part 3 is tilted at an angle with respect to the head 5 so that the head may be moved 65 through the slot 10. The blade is then turned into the position shown in Figure 1, and is moved up against the head in order to cause pins 11 carried by the head, see Figure 3, to enter openings 12 in the blade 6. The pins 70 prevent rotation of the blade 6 with respect to the head.

In addition to the head 5 I provide a locking plate 13, see Figure 4. This plate has a large opening 14 for receiving the part 3, two smaller openings 15 for receiving the pins 11 and a lug 16 receivable in the slot 10. After the blade 6 is moved onto the pins 11, the plate 13 is moved up against the blade so that the slot 10 will receive the lug 16. The 75 blade and plate are now secured to the head 5 by means of a wing nut 17 that is rotatably mounted upon the threaded portion 8.

From the foregoing description of the various parts of the device, the operation there- 80 of may be readily understood.

The plate proper may be of any shape desired so that the device may be used for purposes other than fighting fires. I have found, however, that the blade having teeth 85 18 and a beveled cutting edge 19 is best adapted for fighting forest fires.

I have also explained how the blade may be removed from or attached to the part 3 and how all of the parts are locked in posi- 100

tion by means of the wing nut 17. This type of rigid locking construction for securing a blade to a handle is needed in tools of the character that must accomplish more than ordinary work. The other feature of novelty lies in the fact that the handle 1 has a relatively long metal part which spaces the wooden portion of the handle 2 a sufficient distance away from the blade 6.

10 Although I have shown and described one embodiment of my invention, it is to be understood that the same is susceptible of various changes and I reserve the right to employ such changes as may come within 15 the scope of the appended claims.

I claim:

1. A fire fighting tool comprising a handle having an enlarged end, a blade having an opening for receiving said end, cooperating 20 means carried by said blade and said end for preventing rotation of said blade with respect to said end, a clamping member having a lug receivable in the blade opening and means for moving said member against said 25 blade.

2. A tool comprising a handle having an enlarged head, a blade having a slot for receiving the head, lugs disposed at the ends of the head, said blade having lug-receiving 30 openings, a clamping member slideable on the handle and having a lug receivable in said slot, said member having openings for receiving said lugs, and a wing nut threaded on the handle for bringing the head, blade and clamping member into abutting 35 relation.

3. A tool comprising a handle having an enlarged head, a blade having a slot for receiving the head, lugs disposed at the ends of the head, said blade having lug-receiving 40 openings, a clamping member slideable on the handle and having a lug receivable in said slot, said member having openings for receiving said lugs, and a wing nut threaded on the handle for bringing the head, blade and clamping member into abutting relation, the lug on said clamping member being disposed at one end of said slot while the handle is disposed at the other end of the slot.

4. A tool comprising a blade having a slot 50 therein, a handle having a head insertable through the slot, said head being designed to abut against one side of the blade, a clamping member for abutting against the 55 opposite side of the blade and carrying a lug receivable in the slot, and cooperating means carried by said head, blade and clamping member for preventing the rotation of said blade on said handle.

60 JOHN C. KORTICK.
